UNITED STATES PATENT OFFICE.

HARRY T. BRODEN, OF BROOKLYN, ASSIGNOR TO THE STANDARD CUT GLASS COMPANY, OF NEW YORK, N. Y.

DESIGN FOR A GLASS VESSEL.

SPECIFICATION forming part of Design No. 24,698, dated September 24, 1895.

Application filed August 9, 1895. Serial No. 558,789. Term of patent 7 years.

To all whom it may concern:

Be it known that I, HARRY T. BRODEN, a citizen of the United States, residing at Brooklyn, in the county of Kings and State of New York, have invented and produced a new and original Design for the Ornamentation of Glass Vessels, of which the following is a specification, reference being had to the accompanying drawings, forming a part thereof, 10 in which--

Figure 1 is a plan view of a dish embodying the features of the design, and Fig. 2 is a transverse section taken substantially on the lines 2 2 of Fig. 1.

15 The design is applicable to any kind of glassware, such as bowls, plates, jugs, and dishes.

The leading feature of the design consists in a series of somewhat oval prisms connected 20 to form a star-like chain, and a second series of correspondingly-shaped prisms which cross the first set at each side of their point of juncture, and prismatic star figures formed in the panels obtained by the crossing of the two 25 semioval series of prisms.

The minor feature of the design consists in the inner terminals of the semioval prisms,

being of spear-like formation, and in the checkering around the prismatic star figures, together with cross-hatching and checkering 30 appearing upon the semioval prisms longitudinally of their centers, and in minor prisms and bar figures formed in the smaller inner panels produced by the crossing of the semioval prisms, and similar figures contained outside of the semioval prisms 35 between their outer edges and the outer edges of the dish decorated.

In the center of the dish a panel is formed, in which a button of prismatic character is 40 formed, from which lines depart tangentially, crossing prismatic figures of substantially polygonal shape, circularly arranged, the rosette thus formed being entirely of prismatic character and bordered by prismatic points. 45

I claim--

The design for the ornamentation of glass-vessels, substantially as herein shown and described.

HARRY T. BRODEN.
